UNITED STATES PATENT OFFICE

2,452,720

RAILWAY CAR RETARDER

John A. Bodkin, New York, N. Y.

Application December 10, 1947, Serial No. 790,828

2 Claims. (Cl. 188—62)

1

My invention relates to railroads and, more particularly, to auxiliary devices applied to the rails of railroads.

Objects of my invention are to stop completely or to retard the movement of a car or of an engine rolling along a railroad, and to prevent a car from hitting a terminal bumper or to reduce the impact of such a hit.

Other objects are to provide a stationary device that serves as a retarder or stop for railroad cars, and that serves as a bumper or shock absorber for railroad cars.

Further objects are to achieve these results with a device that can be easily and conveniently applied to any desired part of a railroad track, with a device that can be quickly and securely affixed to the rails of a railroad, and with a device that operates automatically.

Still further objects are to obtain all these results with simple and inexpensive means, and with a device that can be easily made, assembled and maintained in good working condition.

Still other objects and advantages will appear from the following description of an exemplifying embodiment of my invention, from the appended claims and from the accompanying drawing in which:

Fig. 1 shows a top view of a broken off part of a railroad track and of an illustrative embodiment of my invention applied to this track part.

Fig. 2 shows a cross-section of a broken off part of Fig. 1, this cross-section being taken along the line 2—2 in Fig. 1 and being represented on a larger scale.

Fig. 3 shows a cross-section taken along the broken line 3—3 in Fig. 2, parts of the track and of the embodiment of the invention being broken off.

Referring to the drawings, numeral 1 indicates the ties and 4 indicates the rails of railroad which may have standard dimensions. The rails 4 cross the tops of the ties 1 and are affixed to the ties in well known manner which is not shown in the drawings.

A plurality of jaw-like members 5 are applied to the rails 4 and are arranged in pairs. One member 5 of each pair engages one rail 4 while the other member of the same pair engages the other rail 4. Both members 5 of each pair are positioned in a line crossing the rails 4 parallel to and between two ties 1. Each member 5 has an elongated portion 6 extending under and contacting a rail 4. The outer ends of the members 5 form hooks or claws 7 fitting and gripping the outer lower rims 8 of the rails 4.

2

A bolt or rod 9 passes through each pair of members 5 and is threaded throughout its length. Nuts 11 engage both ends of the rods 9 and secure the positions of the rods. Washers 12 are tightly positioned between the nuts 11 and the members 5. Preferably, the washers 12 are of a well known resilient type. The median portion of each rod 9 carries two nuts 13 and two washers 14 positioned at the outer surfaces of the nuts 13.

10 Two auxiliary rails 15 are positioned between the rails 4, each auxiliary rail 15 extending parallel and closely to one of the rails 4. The rails 15 have openings or bores passed by the rods 9 whereby the auxiliary rails are supported by these rods and are slidable in the direction of these rods. This sliding direction crosses the longitudinal directions of the rails 4 and 15 whereby each rail 15 can be spaced from the adjacent rail 4. In the shown position, the rails 15 are in their most outward positions and contact the lower inner rims 16 of the rails 4.

15 The auxiliary rails 15 are urged to this most outward position by compressed coiled springs 17. The springs 17 are wound around the rods 9, each rod 9 carrying two springs 17 which reach from the washers 14 to the two auxiliary rails 15. Preferably, the auxiliary rails are provided with pockets 18 receiving the outer ends of the springs 17.

20 Each auxiliary rail 15 comprises as many cup-shaped projections 19 as there are rods 9. The bottom of each cup 19 contains the opening for the passage of the respective rod. The inner space of the cup forms the pocket 18. Further, each rail 15 comprises a top ledge 21 extending at about the same level as the tops 22 of the rails 4, a bottom ledge 23 connecting the cups 19 and forming bridges over the ties 1, and a wall 24 extending vertically in an oblique direction and connecting the top ledge 21 with the bottom ledge 23 and with the cups 19. Each rail 15 may be reinforced by ribs 25 and 26. Each rib 25 runs from the top ledge 21 to one of the cups 19. The ribs 26 connect the top and the bottom ledge at the two ends of the rail 15.

25 The longitudinal extension of the auxiliary rails 15 is substantially parallel to the rails 4, except that the auxiliary rails have converging end portions 27 which are so bent with respect to the main parts of these rails that they form small angles 28 with the rails 4. Preferably, both ends of the rails 15 are provided with converging portions 27.

30 The springs 17 exert a strong outwardly directed pressure on the rails 4. In order to coun-

teract this pressure, strong braces 29 may be used. Each brace 29 comprises a broad bracket 31 contacting the outer side of the rail 4 under the top 22 of the rail, a reinforcing rib 32 and a base plate 33. This plate is provided with slots or recesses 34 and 35 whereby the brace 29 can be affixed to the respective tie 1 in well known manner by fasteners passing through the slots 34 and 35. These fasteners are well known and are not shown in the drawings.

The described device may be positioned before a terminal bumper or at any other spot of a railroad track where cars should be stopped or retarded. The device operates as follows:

When a car rolls on the rails 4 in the direction to the auxiliary rails 15, the lateral flanges of the car's wheels move along the sides, preferably along the inner sides, of the rail tops 22. These flanges enter the angles 28 whereupon the inner sides of the flanges come into contact with the top ledges 21 of the auxiliary rails 15 and urge the auxiliary rails against the pressure of the springs 17 inwardly as far as necessary to allow the flanges to move ahead between the rails 4 and 15.

While the wheels of the car roll along the rails 15, the springs 17 press the rails 15 against the flanges of the wheels, thereby causing considerable friction between the flanges and the rails 15 on one side and between the flanges and the rails 4 on the other side. This friction brakes or retards the car, consuming all or most of the car's impact or kinetic energy.

The braking power of the device depends on the tension of the springs 17. This tension can be adjusted according to requirement by turning the nuts 13 around the screw rods 9 in the one or the other direction.

I desire it understood that my invention is not confined to the particular embodiment shown and described, the same being merely illustrative, and that my invention may be carried out in other ways without departing from from the spirit of my invention as it is obvious that the particular embodiment shown and described is only one of the many that may be employed to attain the objects of my invention.

Having described the nature of my invention, what I claim and desire to protect by Letters Patent is:

1. A car-retarding railroad appliance compris-

ing a plurality of parallel rods provided with screw threads, a pair of substantially parallel auxiliary rails extending across said rods, being supported by the same and being slidable in the longitudinal direction of said rods, a plurality of pairs of jaw members, the jaw members of each pair being positioned at opposite ends of one of said rods and outside of said pair of auxiliary rails, said rod passing through said jaw members, a plurality of pairs of nuts, the nuts of each pair engaging one of said rods outside of said jaw members whereby said nuts are adapted to press said jaw members against the outer sides of the rails of a railroad while said auxiliary rails are positioned between said railroad rails, and resilient means urging said auxiliary rails outwardly.

2. A car-retarding railroad appliance comprising a plurality of parallel rods provided with screw threads, a pair of substantially parallel auxiliary rails extending across said rods, being supported by the same and being slidable in the longitudinal direction of said rods, a plurality of pairs of jaw members, the jaw members of each pair being positioned at opposite ends of one of said rods and outside of said pair of auxiliary rails, said rod passing through said jaw members, a plurality of pairs of nuts, the nuts of each pair engaging one of said rods outside of said jaw members whereby said nuts are adapted to press said jaw members against the outer sides of the rails of a railroad while said auxiliary rails are positioned between said railroad rails, a plurality of pairs of other nuts, each pair engaging one of said rods at spots located between said auxiliary rails, and a plurality of compressed springs, each positioned between one of said latter nuts and one of said auxiliary rails.
